UNITED STATES PATENT OFFICE.

ARTHUR KLEINFELDT, OF HOBOKEN, NEW JERSEY.

SIPHON FOR DISPENSING LIQUIDS.

No. 824,249.

Specification of Letters Patent.

Patented June 26, 1906.

Application filed June 29, 1905. Serial No. 267,507.

To all whom it may concern:

Be it known that I, ARTHUR KLEINFELDT, a citizen of the United States, residing at Hoboken, in the county of Hudson, in the

5 State of New Jersey, have invented certain new and useful Improvements in Siphons for Dispensing Liquids, of which the following is a specification, reference being had to the accompanying drawings, forming a part hereof.

10 This invention relates to apparatus of the general character of that shown in Letters Patent of the United States No. 706,423, dated August 5, 1902, and adapted for the supply of carbonic-acid gas or other gas under pressure to a liquid-containing receptacle for the purpose of dispensing the liquid under a uniform gas-pressure.

15 The object of the invention is to improve the construction of such apparatus, and particularly to make it possible to fill the liquid-receptacle while the receptacle containing the gas under pressure is in place on the liquid-receptacle and is charged with gas without occasioning the loss of gas, to provide for 20 the automatic relief of excessive pressure in the liquid-receptacle without requiring the use of an independent safety-valve, and to prevent tampering with the apparatus after it has been regulated to give the proper results under the conditions of use.

25 The invention will be more fully explained hereinafter with reference to the accompanying drawings, in which it is illustrated, and in which—

30 Figure 1 is a view of the improved apparatus in vertical central section, showing the gas dome or receiver and in part the liquid-receptacle. Fig. 2 is a detail view showing the controlling-lever in end view. Fig. 3 is a view of a portion of the apparatus shown in Fig. 1, but with the tool or appliance inserted to open the valve in the pipe for the liquid. Fig. 4 is a view similar to Fig. 3, but showing a modification of the structure shown in Fig. 45 3 with parts broken off.

35 The gas receiver or dome or reservoir, adapted to receive a charge of gas under considerable pressure, is mounted upon a cap or plug *b*, adapted to be secured tightly to the 40 mouth of the liquid-receptacle *c*. The cap or plug *b* is provided with a flanged outlet *d*, adapted to have secured thereto a draw-off

45 tap or valve *f*, which communicates, through a passage *g*, with a tube *h* within the liquid-receptacle *c* and extending nearly to the bottom thereof.

50 Arranged in the side of the gas receiver or dome *a* and adjacent to the operating-handle *j* of the draw-off tap is a plug or bushing *k*, provided with a thimble *l*, having therein a 55 passage which communicates with the interior of the dome or receiver *a* and with a pipe *m*, through which the gas may be admitted from the receiver into the liquid-receptacle *c*. The valve *n* is seated in the inner end of the bore 60 of the thimble *l*, its spindle *o* being provided at its outer end with a button or washer *p*, which bears against an elastic diaphragm *q*, held against the end of the bushing *k* by a cap 65 *r* thereon. A spring *s*, surrounding the spindle *o* of the valve *n* and bearing against the washer *p* and a seat formed therefor in the thimble *l*, holds the valve *n* normally against its seat with the button *p* pressed against the diaphragm *q*. A plunger *t*, bearing against 70 the outer surface of the diaphragm *q* or a block carried thereby and supported by the cap *r*, extends outwardly through the latter in position to be engaged by the cam-like end of the pivoted operating-lever *j*, as clearly 75 shown in Fig. 1.

80 The liquid-outlet *g* is closed normally by a valve-plug *u*, which preferably opens outward with the pressure of the liquid and gas in the receptacle *c*, as shown in Figs. 1 and 3, 85 so that it may act as a safety-valve to relieve excessive pressure in the receptacle *c* when necessary, being held to its seat by a spring *v*, which surrounds the stem *u'* of the valve, bearing against the valve-plug *u* and against 90 a sealing-washer *f'*, held in the casing of the tap *f* by a threaded nut *f''*. The valve-stem *u'* is provided above the washer and nut with a forked or slotted head *u³*, through which passes the operating-lever *j*, the head being 95 provided with an adjusting-screw *u³*, by which the action of the lever *j* in lifting the valve *u* may be regulated with respect to its action upon the plunger *t* and the valve *n*.

100 As will be observed by reference to the drawings, the length of the slot in the head *u³* is considerably greater than the width of the lever *j* where it bears against the head, so that the head is capable of movement inde-

pendently of the lever in the direction in which the valve u moves to open. As a convenient means for producing such movement of the head u^2 and of the valve u independently of the movement of the lever for the purpose of moving the valve u from its seat without moving the operating-lever j , and therefore without opening the gas-valve n , a suitable tool or implement x may be provided, as shown in Fig. 3, the same being adapted to be inserted between the upper side of the lever j and the head u^2 to lift the latter away from the lever j . In order that the lever j shall not be disturbed in this operation, it is preferably provided with two bearing-points, as at j' and j^2 , on opposite sides of the fulcrum of the lever, one of such bearing-points, as j' , being preferably slotted, as clearly shown in Fig. 2, for the purpose of guiding and steadyng the implement x when it is being introduced. As shown, the implement consists of a conveniently-formed wire or rod, preferably having its end tapered, as at x' .

Obviously the valve u might be arranged to be opened downward against the pressure in the receptacle c , as shown in Fig. 4, the spring v in this case acting between a lower fixed abutment f^3 and a shoulder u^4 on the head u^2 to hold the valve u normally upward against its seat. In this case the excess of space between the lever j and the head u^2 is above the lever, so that when the implement x is inserted, as shown in Fig. 4, beneath the lever j it forces the head downward in the proper direction to unseat the valve u .

As shown in Figs. 1 and 3 of the drawings, the adjusting-screw u^3 is preferably covered by a key-cap f^4 , screwed on the body f of the tap, which furnishes a seat for the head of the screw to limit the movement of the lever j , and hence the extent of opening of the valves. The cap also conceals the head of the adjusting-screw, so that it cannot be tampered with by unauthorized persons who do not carry the key necessary to remove the cap. If desired, a screw-plug u^4 might be inserted in a hole in the cap, so that by its removal access might be had to the adjusting-screw, which is otherwise concealed.

It will now be understood that whenever it is desired to refill the receptacle c it can be accomplished even if the gas-receiver a is in place and is fully charged, for by the introduction of the implement x the valve u is raised from its seat, as shown in Fig. 3, or is moved downward from its seat, as shown in Fig. 4, to open the liquid-passage without disturbing the valve n . With the valve u open and the valve n closed the filling of the receptacle c with liquid can be proceeded with in the usual manner. As soon as the

implement x is withdrawn the valves u and n are operated simultaneously by the lever j , so that gas from the receiver a is admitted to the receptacle c in proportion to the drawing-off of the liquid from such receptacle. If it be desired to provide the receptacle c with a safety-valve, the construction shown in Figs. 1 and 3 of the drawings is preferred, since the valve u , which is held normally to its seat by the spring v against the pressure from the receptacle c , is permitted to lift and relieve the pressure in the receptacle whenever such pressure becomes excessive.

I claim as my invention—

1. The combination of a liquid-receptacle, an outlet therefor, a gas-receiver connected therewith, a valve to control the passage of gas from the receiver into the receptacle, a valve to control the outlet, means to operate both of said valves simultaneously to admit gas to the receptacle as the liquid escapes therefrom, and independent means to open the outlet-valve to its full extent independently of the gas-valve, substantially as described.

2. The combination of a liquid-receptacle, an outlet therefor, a gas-receiver connected therewith, a valve to control the passage of gas from the receiver into the receptacle, a valve to control the outlet, an operating-lever to act upon both of said valves simultaneously, the outlet-valve having a loose connection with said lever, and means to operate the outlet-valve without moving the lever to open the gas-valve, substantially as described.

3. The combination of a liquid-receptacle, an outlet therefor, a gas-receiver connected therewith, a valve to control the passage of gas from the receiver into the receptacle, a valve to control the outlet, said outlet-valve having a slotted head, an operating-lever adapted to operate the gas-valve and engaged loosely by said slotted head to operate the outlet-valve and means coöperating with the lever and said slotted head to operate the outlet-valve without moving the lever to open the gas-valve, substantially as described.

4. The combination of a liquid-receptacle, an outlet therefor, a gas-receiver connected therewith, a valve to control the passage of gas from the receiver into the receptacle, a valve to control the outlet, said valve having a slotted head, a lever adapted to operate the gas-valve and engaging the slotted head loosely to open the outlet-valve and an implement adapted to be inserted between the lever and the head of the outlet-valve to open the latter without moving the former, substantially as described.

5. The combination of a liquid-receptacle, an outlet therefor, a gas-receiver connected

therewith, a valve to control the passage of gas from the receiver into the receptacle, a tap-valve shell or body, an outlet-valve mounted therein and having a stem provided with an adjusting-screw, an operating-lever mounted in said shell or body to coöperate with the outlet-valve through said screw, and a key-cap engaging said valve shell or body

and covering said adjusting-screw, substantially as described.

This specification signed and witnessed this 26th day of June, A. D. 1905.

ARTHUR KLEINFELDT.

In presence of—

ANTHONY N. JESBERA,
M. A. BRAYLEY.
